METALLIC WATCH STRAP OR SIMILAR ARTICLE

Karl C. Augenstein, Cranston, R.I., assignor to Speidel Corporation, Providence, R.I., a corporation of Rhode Island

Filed July 21, 1960, Ser. No. 61,469

Term of patent 14 years

(Cl. D45—4)

FIG. 2

FIG. 1 is a top plan view of a metallic watch strap or similar article, showing my new design; and

FIG. 2 is a side elevational view, with the conventional end pieces being shown in broken lines.

The underside of the metallic watch strap or similar article is plain and unornamented.

I claim:

The ornamental design for a metallic watch strap or similar article, substantially as shown and described.
